POULTRY STITCHING NEEDLE

Eddie J. Bell, 1455 Highland Ave., Glendale, Calif.

Filed July 25, 1960, Ser. No. 61,495

Term of patent 7 years

(Cl. D11—1)

FIG. 1 is a top plan view of a poultry stitching needle showing my new design,

FIG. 2 is a side elevational view,

FIG. 3 is an end elevational view as viewed from the right hand end of FIG. 2,

FIG. 4 is a greatly enlarged, fragmentary, side elevational view of the piercing point and thread carrying eye, and

FIG. 5 is a vertical, sectional view taken on the line 5—5 of FIG. 4.

I claim:

The ornamental design for a poultry stitching needle, substantially as shown.
